[57] CLAIM

The ornamental design for the combined aquarium and table, as shown and described.

DESCRIPTION

FIG. 1 is a front and top perspective view of a combined aquarium and table showing my new design;

FIG. 2 is a front elevational view thereof, the rear view is identical;

FIG. 3 is a right side elevational view thereof, the left side being a mirror image;

FIG. 4 is a top plan view thereof;

FIG. 5 is a bottom plan view thereof;

FIG. 6 is a front and top perspective view of a second embodiment of FIG. 1;

FIG. 7 is a top plan view of FIG. 6;

FIG. 8 is a bottom plan view of FIG. 6;

FIG. 9 is a left side elevational view of FIG. 6, the right side being a mirror image; and,

FIG. 10 is a front elevational view of FIG. 6, the rear view is identical.
